METHOD OF STOKING LOCOMOTIVES

William Thompson Hanna, Cincinnati, Ohio

Original application June 18, 1928, Serial No. 236,222. Divided and this application June 11, 1936, Serial No. 84,611

8 Claims. (Cl. 110—104)

This invention relates to a method of feeding or stoking fuel to a firebox, and particularly to fire boxes of locomotives, steamboats, etc. This application is a division from my co-pending application Serial No. 236,222, filed June 18, 1928, now Patent No. 2,044,001.

The customary stoking operation for a locomotive includes the steps of unloading the coal from a trough in the tender, crushing it, conveying it forwardly to the proximity of the fuel entrance of the fire box, and presenting it to distributing means which distributes it over the fire bed in the fire box. The present invention is concerned more particularly with a method of distributing fuel over the fire bed in the fire box in a manner to obtain more efficient operation, and with the method of presenting the fuel to distributing means after the fuel has been raised to the proximity of the fuel entrance of the fire box.

In order to overcome disadvantages that have existed in the firing of a locomotive and to obtain more efficient and complete combustion of fuel, it is desirable that the fuel be presented to the fire bed continuously, but in such a manner that respective areas receive fuel in allotments spaced at approximately equal intervals of time, so that the previously delivered portion of fuel to any given area is allowed sufficient time to start burning before the next allotment arrives. In addition, the various sections of the fire bed should receive approximately equal amounts of fuel in order to maintain a level and uniform bed, thereby preventing short-circuiting of the draft through thinner portions of the bed. It is one of the objects of this invention to provide a method for feeding fuel to a fire bed in such a manner as to increase the efficiency of combustion and to provide a method by which the fuel may be distributed evenly over the entire bed as desired.

Another aspect of the invention has to do with the proportioning of the distribution of the coal over the fire bed. Short-circuiting of the draft is especially prevalent through the sides of the fire bed because of the design and construction of the customary grate used to support the ashes in the fire box of a locomotive. Therefore, it is desirable to build the bed higher at the sides than at the center, in order to prevent such side drafts. Thus, it is another object of the invention to provide a method for feeding the fuel to a fire bed in such a way that enough fuel is distributed to the sides of the fire bed to bank the sides to prevent excessive draft thereat.

These, and other apparent objects and ad-

vantages, are obtained by the methods and the apparatus for carrying out the methods described in the following specification and disclosed in the accompanying drawings, in which:

Figure 1 shows a vertical sectional view of a stoker mechanism, adapted to carry out the invention, taken substantially on a longitudinal center line;

Figure 2 is a vertical transverse section of the same, taken substantially on a line 2—2 of Figure 1;

Figure 3 is a horizontal section of the same, taken substantially on a line 3—3 of Figure 1;

Figure 4 is a side elevation partially in vertical longitudinal section, showing the stoker mounted on a locomotive and a tender;

Figure 5 is a top plan view of the interior of the housing of Figure 1; and

Figure 6 is a vertical section taken on line 6—6 of Figure 3.

The arrangement of the various components of a stoker mechanism for carrying out the method of feeding fuel hereinafter described, in accordance with this invention, is illustrated in Figure 4 of the drawings. Fuel in the tender falls into a fuel trough 8, mounted beneath the tender, and is moved forwardly through the trough 8 and conduit 6 by conveyor 7 and 5, respectively, through extension 4 which extends in a forwardly and upwardly direction to fuel housing 3. Housing 3 embraces the usual firing opening 2 in the back head 1 of a locomotive fire box and contains fuel-manipulating means 14 and 15 (Figures 1-3), supported therein. These fuel-manipulating means condition the fuel entering the housing from extension 4 and present it over a ledge or spillway 3a to fuel-distributing mechanism, generally indicated at 18, which distributes the fuel over the fire bed in accordance with the manner in which the fuel is presented.

Conveyor 5 is rotatively supported in conduit 6 with its rearward end operatively connected to the forward end of conveyor 7 which, in turn, is suitably supported for rotation in trough 8. Conveyor 7 carries a gear 10, through which it is driven by a shaft 11 suitably mounted for rotation on the frame of the trough 8. Shaft 11 carries a gear (not shown) which engages the gear 10. Shaft 11 has operative engagement with a steam motor, or other source of motive power, 12, through suitable connections as, for example, the telescopic shaft 13. The fuel-manipulating means 14 and 15 are also rotatively actuated by motor 12 through shafts 60 and suitable gearing 55.

contained in housing 31, as shown in Figures 1-4.

Conduit 6 is arranged to have a greater cross-sectional area than the outlet of trough 8, and extension 4 is arranged to have an increasing cross-sectional area as it approaches the firing opening (see Figure 3). Likewise, housing 3 has an upwardly increasing cross-sectional area to prevent clogging and its rear wall 3d is inclined 10 forwardly toward the fuel entrance 2 of the fire box in order to force and direct the flow of fuel rising through the housing forwardly toward the fuel-manipulating means 14 and 15. In addition, the housing is so constructed and contoured as 15 to aid in carrying out the method of feeding fuel herein described.

The connections between hopper 8 and conduit 6, and between conduit 6 and extension 4, are of the ball and socket type, with a provision for the 20 sliding of the conduit 6 with respect to the extension 4. This provides a substantially universal joint connection in the conduit between the fuel supply in the tender 9 and the fire door housing 3, whereby movement of the tender with 25 respect to the locomotive is accommodated.

Turning now to consideration of the distributing mechanism 18 which, in the embodiment of the invention herein described, is mounted inside the firing opening of the fire box directly in 30 front of and below ledge 3a. This distributing mechanism comprises two portions, a screening and steam jet projector member 19, which is termed a blast chamber, and a distributor plate 31.

35 The blast chamber 19 (Figures 1 and 2) is pivotally supported directly above the distributor plate 31 in the firing opening on pipes 18a and 18b by pipe sections 23 and 24 which are journaled in the side walls of housing 3. These pipes 40 respectively conduct high and low pressure steam to the blast chamber 19 which comprises a plurality of steam jets arranged in two parallel horizontal planes. The upper portion consists of a series of fingers 19a arranged in a fan-like formation with high-pressure steam jets 19b issuing from the extremities thereof. An aperture 22 is arranged substantially along and underneath the bases of the fingers through which low-pressure steam escapes in a ribbon-like jet across the 45 upper surface of the distributor plate 31.

The distributor plate 31 is of a design which 50 serves to distribute the fuel descending upon it through the blast chamber fingers 19a over the fire bed in an efficient manner. In order that the distributor plate may serve to direct the fuel more effectively to cover the back corners of the fire bed, it is provided with the channels 31e curving toward the side of the fire box. In addition, its position longitudinally with respect to 55 the fire bed may be varied by means of crank shaft 34, Figure 1, suitably journaled in a bearing on housing 3 and having a handle 34a and an arm 35 keyed therewith, which latter is linked to the distributor plates by means of links 36.

60 This construction of the blast chamber 19 and distributor plate 31 permits new and highly advantageous results. For example, as the mass of fuel (which consists of a heterogeneous mixture of large and small particles) flows over the ledge 65 3a onto the blast chamber 19, the fingers 19a act to screen the fuel to separate the larger from the smaller particles whereby the larger particles flowing over the ends of the fingers 19a are picked up by the high-pressure jets 19b of steam 70 75 issuing therefrom and are carried to the far parts

of the fire bed, but are not carried out of the fire box into the stack of the locomotive, the steam pressure being controlled to prevent such operation. The smaller particles falling between the fingers 19a onto the surface 31 do not come 5 into contact with the high-pressure jets 19b, but are picked up by the low-pressure ribbon jet of steam issuing from the slot 22 and are swept over the surface 31. Thus, they are effectively scattered to all parts of the fire bed without being carried out of the stack by the high-pressure jets. As the low-pressure jets expand upwardly, and the high-pressure jets expand downwardly, the two meet in a neutralizing zone, which also aids in the desired distribution of 15 the finer particles over the fire bed.

In order to accomplish the above described screening operation efficiently, and to insure the fuel being projected from the distributing mechanism 18 to the zone for which it is intended 20 when it is supplied to this mechanism, the fuel is placed on the top of the blast chamber 19 whence it descends, due to the gravitational force 25 acting upon it, over the screening members and into the influence of the high or low-pressure steam jets, in accordance with a particular size of the particles, and thereby is distributed over the fire bed. If the fuel is dropped or forcibly projected toward the blast chamber, the screening 30 is less effectual and the resulting distribution may be uncertain and inefficient.

For the proper operation of the fuel-distributing mechanism 18, the fuel supplied thereto should be properly conditioned by some fuel-conditioning mechanism. It is common practice 35 on many railroads to use in locomotives what is known as "run of the mine" coal which is a mixture of pieces of all sizes, from large lumps to fine particles. This fuel is more or less cohesive, particularly when wet, and in its passage 40 through the conduit from the tender hopper to the housing in proximity of the firing opening, it is subjected to considerable pressure which acts to compact the mass into a solid body or column. Upon entering the housing, this column normally 45 tends to rise until its free end comes into contact with the wall of the housing extending over the conduit, whereupon the top of the column breaks off and falls in a large chunk or in chunks, which are not efficiently handled by the distributing 50 apparatus. To eliminate the possibility of such masses of fuel falling on to the distributor plate 31, the method of the present invention provides for transforming the fuel rising in the conduit 4 into form relatively thinner than the bulk of the 55 fuel in the conduit. That is, its form is changed as to thickness, or density, consistency, etc., and the fuel reaches the distributing mechanism 18 in a manner and condition conducive to efficient distribution over the fire.

To carry out this method there is provided 60 within the housing 3 fuel-conditioning and regulating means comprising a pair of tapered rotary vanes or worms 14 and 15 which not only break up and thin the mass but act to spread or otherwise condition the loose fuel before the firing opening so that it may pass freely over the ledge 3a in a manner somewhat similar to a fluid passing in lateral waves over a spillway. The vanes 14 and 15 are suitably journaled in cap plates 65 16 and 17, forming part of the side walls of the housing, and are preferably so positioned relative to the housing and the firing opening as to cause relatively little resistance to the flow of fuel.

In addition, in the method of the present in- 75

vention, fuel is preferably removed by the vanes 14 and 15 in the form of successive ribbon-like masses from the under-side of the column rising in the elevating conduit 4, whence each mass is moved endwise over the ledge 3a to the distributing apparatus 18. This method is carried out by providing the housing 3 with recesses generally indicated at 111 and 112 respectively, in either side of the wall 3c of the housing adjacent the back head 1. The worms 14 and 15 are mounted in these recesses. The recesses 111 and 112 have conically-shaped concave fuel-supporting surfaces 113 and 114 respectively, the surfaces being concentric with surfaces containing the respective peripheries of the vanes 14 and 15. In this way, the vanes 14 and 15 are, in effect, recessed in the front wall 3e of the housing 3 and, to some extent, are removed from the direct path of the fuel. The surfaces 113 and 114 intersect the surface of the forward wall 3e of the housing 3 to form edges or ledges 115 and 116, respectively, over which the fuel rising from the extension 4 flows into the recesses 111 and 112 to be acted on by the worms 14 and 15, respectively. Further, the back wall 3d, Figure 1, of the housing 3 preferably slants toward the front wall thereof, generally indicated at 3e. This sloping rear wall 3d causes a forward pressure to be exerted on the rising fuel column, causing it to flow toward the sides 3f of the housing and consequently over the edges 115 and 116 into the recesses 111 and 112 and into the range of the fuel-manipulating elements 14 and 15. As each vane rotates, it carries the fuel lying on it in the form of a spiral ribbon-like mass around and deposits it endwise over the ledge 3a.

Another feature of the method of the present invention provides for feeding more fuel to the sides of the fire bed than to the central area thereof, and this method is carried out by the apparatus described, wherein the worms 14 and 15 are shown as tapering toward their unmouted or free ends. With this construction, the fuel-handling capacity of each worm is greater at its mounted end (where the vane is largest) than at its free end (where the vane is smallest) and so, as fuel moves from the mounted toward the free end of each worm, it is caused to move away from the worms and is delivered over the ledge 3a.

The method of the present invention also provides for firing respective areas of the fire bed with fuel allotments spaced at approximately equal time intervals so that the previously delivered portion of fuel to any given area is allowed time to start burning before the next allotment arrives. This method is carried out by the operation of the worms 14 and 15. Each revolution of the respective worm undermines the mass of fuel from the under-side of the rising fuel column and conveys the mass forwardly and upwardly on one of the vanes of the worms along the concave fuel-supporting surfaces 113 and 114 of the housing 3 to the spillway 3a, over which this portion of fuel falls onto the blast chamber 19 of the distributing means 18 in a wave which moves laterally from the respective sides of the fire door opening to the center thereof, and is then distributed to the fire bed in a manner in accordance with the way in which it was presented to the distributing means. The coal thus presented to the distributing means is blown from it over the fire bed in a succession of shower bands, each shower band extending lengthwise of the fire bed and moving thereacross from the side of the fire bed in one direction only, so that continuous fir-

ing is obtained without firing "green" coal on green coal.

While I have shown and described a particular embodiment of a construction for carrying out the invention as applied to a locomotive stoker, it is to be understood that the same is for the purpose of illustration only, and that I am not limited to the detailed features thereof, as it is understood that the construction may be variously modified and altered without in any manner departing from the spirit and scope of the invention, as set forth in the appended claims.

I claim:

1. The method of coal firing a locomotive fire box which comprises projecting the coal into the fire box in a succession of shower bands following each other in sequence, each shower band extending lengthwise of the fire box, and moving each shower band from one side of the fire box thereover in one direction only, whereby successive regularly intermittent coal showers are precipitated upon the various portions of the fire bed.

2. The method of coal firing a locomotive fire box which comprises projecting the coal into the fire box in a plurality of shower bands extending lengthwise of the fire box, and moving each shower band in one direction only from its respective side of the fire box toward the longitudinal center line thereof whereby successive and regularly intermittent coal showers are precipitated upon the various portions of the fire box.

3. The method of coal firing a locomotive which comprises projecting the coal into the fire box in a plurality of shower bands extending lengthwise of the fire box, moving each shower band from its respective side of the fire box toward the longitudinal center line thereof whereby successive and regularly intermittent showers are precipitated on the various portions of the fire box, and diminishing the fuel mass of each of said shower bands as it progresses toward the center line of the fire box.

4. The method of coal firing a locomotive which comprises projecting the coal into the fire box in a plurality of shower bands extending lengthwise of the fire box, moving each shower band from its respective side of the fire box toward the longitudinal center line thereof whereby successive and regularly intermittent showers are precipitated on the various portions of the fire box, and varying the fuel mass of each of said shower bands in accordance with the predetermined desired proportion of fuel in the fire bed.

5. The method of coal firing a locomotive fire box through a firing opening therein comprising continually moving coal to the firing opening, coal in the form of a rising sloping column, continually removing successive portions from the underside of said column each portion being in the form of an extended ribbon-like mass, moving each said ribbon-like mass through said firing opening in such manner that it advances endwise through the opening and at an acute angle to the general fuel movement, and blowing the fuel thus moved through the firing opening over the fire bed of the fire box.

6. The method of coal firing a locomotive fire box through a firing opening thereof, comprising continuously moving the coal to said firing opening in the form of a rising sloping column, maintaining the top of the column approximately level with the firing opening, successively segregating and removing portions from the underside only of said coal column, raising the portions of coal thus successively removed to and spilling them over

the lower edge of the firing opening, screening by gravity the coarse particles from the fine as they fall and projecting the coarse particles and the fine particles separately over the fire bed.

5 7. The method of coal firing a locomotive fire box through a firing opening thereof, comprising continually moving comminuted coal to said firing opening in the form of an advancing column, successively segregating and removing portions from 10 one side only of said column, manipulating each portion into a relatively extended ribbon-like row of particles, raising each such row of particles to said firing opening in angular relation thereto, and moving said rows of particles into said opening in lateral progression, screening by gravity the coal particles thus presented to separate the fine from the coarse, and projecting the fine and coarse particles thus separated over the fire bed.

15 8. The method of coal firing a locomotive fire

box which comprises advancing coal in a columnar mass in effective proximity to a firing opening of the fire box, successively removing portions from a side of said columnar mass and manipulating the coal of each portion into extended ribbon-like formation, advancing each successive portion so formed through the firing opening in a forwardly moving stream and simultaneously causing the stream to travel laterally from the side of the firing opening toward the longitudinal center line thereof, and projecting the coal particles of the stream over the fire bed in a shower band extending lengthwise of the fire box and moving unidirectionally thereover from one side of the fire box toward the longitudinal center line 10 thereof, whereby successive intermittent deposits of coal are precipitated progressively upon the various portions of the fire bed.

15 WILLIAM THOMPSON HANNA.
